(57) **CLAIM**

The ornamental design for a temperature indicating strip, as shown and described.

DESCRIPTION

FIG. 1 is a front elevation view of the temperature indicating strip of the present invention;

FIG. 2 is a front elevation view of a second embodiment of the temperature indicating strip of the present invention;

FIG. 3 is a front elevation view of a third embodiment of the temperature indicating strip of the present invention;

FIG. 4 is a front elevation view of a fourth embodiment of the temperature indicating strip of the present invention; and,

FIG. 5 is a front elevation view of a fifth embodiment of the temperature indicating strip of the present invention.

The drawing is lined for color. The broken lines are intended to show environmental structure and form no part of the claimed design. The top, bottom, sides and back form no part of the claimed design.
